UNITED STATES PATENT OFFICE.

OTTO A. SCHMITT, OF BALTIMORE, MARYLAND.

MACHINE FOR MAKING BOX-BLANKS.

1,355,430.

Specification of Letters Patent.

Patented Oct. 12, 1920.

Application filed July 29, 1919. Serial No. 314,114.

To all whom it may concern:

Be it known that I, OTTO ANDREW SCHMITT, a citizen of the United States of America, residing in the city of Baltimore, 5 State of Maryland, have invented certain new and useful Improvements in Machines for Making Box-Blanks, of which the following is a specification.

This invention relates to a machine for 10 cutting and scoring box blanks in the manufacture of paper boxes, the same being an improvement on and reorganization of the machine described in U. S. Patent No. 1,143,672. The machine is particularly 15 adapted for use in the manufacture of boxes usually made of corrugated board and reinforced at the edges by means of plaits or folds in the material, the box referred to being of the general type described in 20 U. S. Patent No. 1,063,845. The machine is however, capable of a broader and more general application.

The box illustrated in the Patent No. 1,063,845 is reinforced by means of plaits or 25 folds extending along the corners, which term in the present instance refers to the lines formed by the intersection of two sides rather than to the points formed by the intersection of three sides, and while all the corners of the box may be thus reinforced, 30 in the preferred form of the invention, the plaits extend along the top and bottom corners or horizontal edges only.

In the manufacture of such boxes, the 35 blanks are preferably first plaited, that is, the two reinforcing folds are formed in the blank, the same being parallel and extending the length of the blank in the type of box just described, and spaced apart by a distance equal to the height of the finished box. 40 These plaits are preferably sewed or otherwise fastened to make them permanent. The paper on each side of the plaits is to be utilized as flaps forming the top and bottom 45 of the box.

The machine of the present application is intended to operate on the plaited blanks as described, cutting the flaps and forming the corners. An important difficulty encountered 50 in the manufacture of boxes of this type is in the bending of the plaited portions of the paper at the corners. Where the paper is thus thickened, the outside fibers give way in bending and the corners break. This

difficulty in itself has been overcome by the 55 provision of the corner-forming device described in U. S. Patent No. 1,143,672, but in the machine therein described, the corner-forming dies 16 were mounted on the knife carriers to move in unison therewith. The 60 knives preceded the corner-forming dies but they operate immediately adjacent the dies and must be withdrawn through the paper gathered by the dies immediately adjacent the corners, and it is found that injury to 65 the edges of the flaps results making the product of unpleasing appearance and less than maximum strength. To overcome this difficulty and perfect the product, the machine has been reorganized as hereinafter described. 70 The corner-forming and flap-cutting functions are performed by the single machine as previously. The flap-cutting operation precedes the formation of the corners, the knives being withdrawn prior to 75 the corner-forming operation.

In the preferred form of the invention as shown, the cutter or knife and the die are mounted to move in unison but they are oppositely disposed so that they operate, one 80 on the forward, and the other on the return stroke. Coöoperating with the cutter is a suitable cutting block and die and coöperating with the die is a suitable internal former.

In the accompanying drawings I have 85 illustrated a cutting and scoring machine embodying my invention in the preferred form.

Figure 1 is a front elevation of the machine with the table cut away; 90

Fig. 2 is a side elevation;

Fig. 3 is a plan with the left half of the upper beam removed;

Fig. 4 is a detail view showing the internal corner-former and die in side elevation; 95 the die being in its withdrawn position;

Fig. 5 is a transverse section through the drive shaft showing the clutch in elevation;

Fig. 6 is a longitudinal section at the 100 same point;

Fig. 7 is a perspective of the clutch pin;

Fig. 8 is a view of the brake taken on a plane transverse to the drive shaft;

Fig. 9 is a section on the line 9, 9 of Fig. 105 1, the same being on a plane parallel to the planes of Figs. 2 and 4 looking in the direction of the arrows, showing the knife

and cutter block with the corner-forming dies in the rear of the plane of the section; and

Fig. 10 is an enlarged section through the cutter block.

Referring to the drawings by numerals, the machine which in general terms is called a press, is driven by means of a belt 1 running on a pulley 2 fast on the shaft 3, see Fig. 5, to which is keyed a pinion 4 meshing with the toothed gear 5 which is loose on the drive shaft 6. This gear 5 cooperates with a clutch 7 secured to the shaft 6 by any suitable means as a key 8. As an engaging means for the clutch, the gear 5 carries on its face disposed toward the clutch member, a plurality of abutments 10. In the present instance, there are four of these in the form of bolt heads, the bolts 11 being seated in the gear hub parallel to the shaft. These abutments 10 may of course be provided in any suitable manner, the arrangement described, *i. e.*, the use of the bolts, being chosen because it makes it possible to use the toughest metal having the greatest resistive properties for the clutch abutments 10 with an ordinary cast iron or cast steel gear. The clutch member as shown, consists of a cast iron central portion or body 12 inclosed by spaced steel bands 13. The body portion has a peripheral groove or dog path 14 between the bands and a longitudinal slot or groove 15 for a sliding clutch bolt 16, held in its seat by the bands 13. Also, there is a peripheral seat 17 in which is secured a circular or segmental leaf spring 18 which engages the end of the bolt remote from the gear 5, imparting to it a tendency to slide through the slot to the right and causing it, unless otherwise restrained, to engage with its end surface 19 the adjacent surface 20 of the gear. In this position, it projects into the path of the abutments 10 by one of which it would in this position be engaged, thus rotatively connecting the gear 5 to the clutch member and hence to the shaft. The operation of the clutch is controlled by a tapering dog 22 carried by an arm 23 on the dog shaft 24 which is operated by the pedal 25, see Fig. 2, the latter being normally raised by the spring 26 which thus controls the annular position of the shaft 24, swinging the arm 23 which is on the opposite side of the shaft, downward to the left, *i. e.*, counter-clockwise, and holding the dog 22 in the dog path or groove 14, it being understood that the steel rings 13 are spaced apart to expose the path 14 while they at the same time cover the longitudinal slot 15 holding the clutch pin or sliding bolt 16 in the slot. This sliding bolt or pin 16 is notched transversely at 27, more or less in registration with the groove 14 when the pin is withdrawn. One corner of the notch is rounded

or cut off at 28 to provide for the entrance of the dog, giving a cam action by which the dog 22 co-operating with this cam surface 28, serves to withdraw the pin as the clutch rotates, sliding the curved surface of the notch in the pin over the inclined surface of the dog.

Normally, the dog 22 is held in the path or groove 14 in the clutch by means of the spring 26. When the dog takes this position, the clutch member is rotated until the dog, which is wedge-shaped, enters the notch 27 in the sliding bolt 16 and by engaging the cam surface 28 in the notch withdraws the pin from the path of the abutments 10 on the gear, releasing the clutch and the gear 5 so that it rotates free of the shaft.

The drive shaft 6 also carries a brake drum or disk 30 encircling which is a brake band 31 shown as suitably lined with resistive fabric 32. Tension is applied to the band by means of a bolt 33 swiveled in one end of the pin and threaded in the other. This brake band 31 has a radially projecting arm 34 secured to the frame by means of bolt 21 to prevent rotation of the band. This brake serves to check immediately the rotation of the drive shaft and hence the functioning of the moving parts of the machine immediately on the release of the clutch.

Referring to Fig. 2, it will be noted that the drive shaft 6 is enlarged at both ends to form crank disks or solid cranks 35 mounted in suitable bearings 44 in each of the end frames 45 which are suitably secured together to form a rigid frame for the machine. The crank disks carry crank pins 36 with which co-operate upright connecting rods 37 carrying wrist pins 38 seated in cross-heads 39 moving in vertical ways 40. The cross-heads 39, referred to as the lower cross-heads, are connected each by a rigid upright rod or shaft 41 with an upper cross-head 42 sliding in vertical ways 43. The lower cross-heads carry the lower transverse beam 46 extending from end to end of the machine, and the upper cross-heads carry the upper transverse beam 47 likewise extending from end to end of the machine. These beams of course reciprocate with the corresponding cross-heads 39 and 42 maintaining a uniform relation to each other. The upper beam 47 has at its lower edge a transverse horizontal way or rail 49 on which are mounted knife carriages 50, carrying the depending, downwardly disposed knife blades 51 rigidly but removably secured to the bottom edge of the carriage. In the form shown, each knife carriage has secured thereto a rack 52 engaged by a toothed pinion 53 having a bearing in the beam 47. Each pinion is controlled by a suitable hand wheel 154 by the rotation of

which the knives may be moved to the desired position of adjustment to conform to the height or depth of the particular boxes being made. The knife carriages are secured in adjusted position by set screws 54 seated in the carriages and engaging the ways when turned up to clamping position. Beneath the knives 51 mounted for adjustment in suitable ways 55 in a stationary table 60 parallel to the ways 49, are the cutting blocks 56. There is a block corresponding to each knife, separately adjustable as hereinafter described, and each block is slotted at 57 to admit the knife. The slots are wide enough to provide clearance and their edges are armed with hard steel cutting members 58 having edges 59 which project over the slot in close relation to the cutting blade in its cutting position. These cutting members are secured to the blocks by screws 61.

Each cutting block in the form of the invention shown, carries a rack 62 meshing with a pinion 63 on a transverse shaft 64 having suitable bearings in the table at 65 and provided with a hand wheel 66 by means of which the block may be moved along the ways to adjusted position. The cutting blocks are held in adjusted position in the ways by means of set screws 68 which bear against friction plates 120 which in turn serve to transmit the pressure of the screws to the cutting blocks. The cutting members 58 are adjusted laterally, *i. e.*, toward the blade, to take up wear, by means of horizontal transverse screws 69 seated in the cutting members and having their heads 70 located in notches or recesses 71 in the cutting blocks, the adjustment resulting from the pressure of the screw heads against the vertical ways 72 of the notches being very slight and dependent upon the slight play existing between the cutting members 58 and the blocks.

The knives 51 are provided to cut the flaps and are made adjustable each toward and from the other in the direction of their length, *i. e.*, from right to left in Fig. 1, so that they may be always spaced apart by a distance equal to the height of the boxes being made. When the parts are in adjustment, the cutting blocks are directly beneath the corresponding knives, that is, the slot 57 in the block is open at one end, the end disposed toward the center of the machine making the block in effect U-shaped in plan so that the spacing of the cutting blocks conforms exactly to the spacing of the knives. This leaves a space or opening at the center of the table through the ways 55, equal in length to the height of the finished box and in width to the width of the ways. Through this opening, the corner dies 75, which operate on the up-stroke, reciprocate vertically and come at the top of their traverse into

cooperative relation with the internal corner-formers 76, for a detail view of which part see Fig. 4.

The knives are mounted on the top reciprocating beam 47 and the corner dies 75 are mounted on the lower reciprocating beam 46, it being understood that these two beams are rigidly connected, moving up and down together. The vertical relations of the cutter knife, corner dies and internal corner former are shown in Fig. 9, the knife 51 being directly in front of the internal corner former 76, and the cutter block 56 in front of the die 75. The internal corner formers 76 are mounted on the stationary supports 77 secured to the rods 78 which are seated at their ends in the end frames 45. The supports 77 engage the rods by means of split bearings 79 closed by set screws 80. By loosening the set screws, the bearings may be opened to sliding relation with the rods and the supports moved to the desired position in relation to the knives and clamped by tightening the screws. This position, in the operative adjustment of the machine, is close to the knives and just out of contact as shown in Fig. 1.

To accommodate the corner die 75, the beam 46 has its top edge formed with a way or rail 82 having its center line directly beneath the knife and internal former 76. On this way or rail, the dies 75 are mounted as illustrated in Fig. 4, the dies having a two-sided groove 83 to receive the rail or way, the third side of the groove which is 100 of dovetailed cross-section to correspond to the rail or way, also dovetailed, being formed by a clamping block 84 secured to the side of the die block by means of set screws 85. When the set screws are 105 loosened, the die may be slid along the way or rail at will, and when they are tightened, the dies are held in adjusted position, the die being clamped to the rail. Adjusted position is directly beneath the former 76. 110

The corner-forming die 75 is similar in principle to the corresponding die described and shown in the Weiss and Dewling Patent No. 1,143,672, but improved as to certain details, that is, each die consists of 115 two gathering fingers 86 at each side, each being mounted on a pivot 87 parallel to the drive shaft. The pivots are at one end and the fingers have their opposite or swinging ends 88 rounded to engage and gather the 120 material without cutting or punching it. Adjacent the pivots 87 are stops 89 on the die block engaged by stops 90 on the fingers. The fingers are controlled by spring-pressed sliding knuckles 91 actuated by springs 92 125 in the block and the center of the corner fold is flattened by an adjustable abutment 93, the adjustment being accomplished by means of a vertical set screw 94 controlled from the bottom of the block, the abutment 130

93 moving for purposes of adjustment in the vertical ways 95.

The internal former 76 is provided with a vertical shank 97 sliding in a suitable 5 socket 98 in the support 77. The former is adjusted as to its vertical position by the direct thrust of a vertical set screw 99 which enters the support from above and is held in adjusted position by a horizontal set 10 screw 100 which bears against the shank 97.

The vertical adjustment of the abutment 93 and the internal former 76 makes it possible to press the material forming the corners to the desired shape without cutting or 15 weakening it.

Referring to Fig. 3, it will be noted that in addition to the parts already described, I have shown the table 60 provided with 20 two sets of gages 105 shown in operative position and 106 shown in inoperative position. Both sets are adjustable along the table, that is, in the direction of the drive shaft, and having guide surfaces 107, 108 at right angles to the drive shaft.

Having reference to the operation of the machine, it has been pointed out that on each side of the machine, running in vertical guides to the end frame 45, are two reciprocating cross-heads 39 and 42, the upper 30 and lower cross-heads 39 and 42 at each side of the machine being rigidly connected by the rod 41. The upper cross-heads 42 on the opposite sides of the machine are connected by the upper transverse beam 47 and the lower cross-heads on each side of 35 the machine are connected by transverse beam 46 so that in the operation of the machine or press, the upper and lower beams 46, 47 reciprocate vertically in unison, being 40 in fact the upper and lower members of a reciprocating frame.

The flap-cutting knives 51 are downwardly disposed and carried by the upper beam and they coöperate with the cutting 45 blocks 56 on the stationary table 60. The corner dies 75 on the other hand, are upwardly disposed and carried by the lower beam. They reciprocate through the opening 50 in the ways 55 between the adjacent ends of the cutting blocks 56, the internal 55 corner-formers 76 which coöperate with the corner-forming dies 75 being mounted on stationary supports 77 above the table. All the cutting and forming members have a suitable adjustment as already described.

The dog 22 controlling the clutch 7 is normally held in the path of the pin 16 by means of a spring and when in this normal position, it holds the pin out of engagement 60 with the abutments 10 on the pulley 5. When the machine is to be operated, the dog 22 is lifted from normal position by pressing the foot on a suitable pedal. As soon as the operation is completed, the pedal is released

and the dog drops into position. When the 65 pin 16 comes into contact with the dog which is a wedge engaging the slot 27 in the pin, the latter is withdrawn, the clutch released and the machine stops instantaneously owing to the action of the brake 30, 31. 70

The plaited blanks are fed with the inside, *i. e.*, what is to be the inside of the completed box, uppermost. By reciprocation of the frame, including the beams 46, 47 carrying at the top the downwardly disposed knives, and at the bottom, the upwardly disposed corner dies, the downward stroke cuts the flaps and the upward stroke withdraws the knives and bends the plaits at the corners, *i. e.*, forms the corners. If it 80 is desired to score the paper between the top and bottom plaits, a scoring member between the dies is very conveniently provided as in the machine of the patent cited.

As the knives operate during the latter 85 half of the down stroke and are withdrawn during the first half of the up stroke, this part of the operation of the machine is referred to as the working stroke of the cutters, and as the dies operate during the last 90 half of the up stroke and are withdrawn from operative position during the first part of the down stroke, this part of the operation of the machine is referred to as the working stroke of the dies. 95

One of the important points in the operation of the machine is to have it so timed that the cutting operation takes place and the knife is withdrawn prior to the action of the dies. This prevents dragging of the 100 knife through the gathered folds of the paper with consequent injury to the product; wherefore, the provision of the automatic clutch and brake in connection with the arrangement of the knives and dies on the 105 upper and lower simultaneously moving beams 46 and 47.

The timing of the parts is such that the pin 16 reaches the point on the incline 21 of the dog at which it is drawn free of the 110 abutments 10 on the gear 5, when the knives and dies have started on the downward stroke so that the knives are still sufficiently elevated to admit the blank without difficulty, and the dies 75 are withdrawn out 115 of the way and preferably beneath the table 60. Whenever the pedal 25 is depressed, the dog is withdrawn and the machine continues to operate until this pedal is released, returning the dog to the path 14. 120 In this position of the dog, the machine continues to operate until the parts arrive in the position described when the pin is withdrawn, the clutch released and the operation 125 of the machine arrested by the brake as already described. In this position, the paper is inserted and the pedal depressed as already described, and the operation com-

pleted to the satisfaction of the attendant, the pedal released, the paper withdrawn and the operation repeated.

I have thus described my invention specifically and in detail in order that its nature and operation may be fully understood; however, the specific terms herein are used descriptively rather than in their limiting sense and the scope of the invention is defined in the claims:

1. In a machine for cutting the flaps and forming the corners of a box blank, a reciprocating knife, a reciprocating corner-forming die with means for actuating the knife to complete its working stroke and the die to complete its working stroke during separate periods of time, and means for arresting the movement of the parts just prior to the cutting operation.

2. In a machine for cutting the flaps and forming the corners of a plaited box blank of corrugated paper, a reciprocating knife and a reciprocating corner-forming die with means for actuating both members to operate and withdraw during separate successive periods of time and means for arresting the movement of the parts just prior to the cutting operation.

3. In a machine for cutting the flaps and forming the corners of a plaited box blank of corrugated paper, a reciprocating knife and a reciprocating corner-forming die with means for actuating both members to operate and withdraw during separate successive periods of time, means for disconnecting the actuating means, and means for arresting the movement of the parts just prior to the cutting operation.

4. In a machine for cutting the flaps and forming the corners of a plaited box blank of corrugated paper, a reciprocating knife and a reciprocating corner-forming die with means for actuating both members to operate and withdraw during separate successive periods of time, and means for arresting the movement of the parts at a fixed predetermined point in the operation.

5. In a machine for cutting the flaps and forming the corners of a box blank, cutters and external dies, oppositely disposed means for causing the same to operate successively, and means for arresting the movement of the parts just prior to the operation of the cutters.

6. In a machine for cutting the flaps and forming the corners of a box blank, cutting members including a knife and a cutting block, corner-forming members including an external die and internal corner-former, reciprocating means carrying one said cutting member and one said corner-forming member oppositely disposed so that cutting and forming take place on alternate strokes of the reciprocating means, the other co-operating cutting member and the other cor-

ner-forming member being stationary, and means for arresting the motion of the parts just prior to the operation of the cutting members.

7. In a machine for cutting and forming box blanks, reciprocating means, co-operating moving and stationary cutting members, co-operating moving and stationary corner-forming dies, the moving cutting member and the moving corner-forming die being oppositely disposed and carried by said reciprocating means, means for driving the reciprocating means, and means for discontinuing the operation of the machine just prior to the meeting of the cutting members.

8. In a machine for cutting and forming box blanks, reciprocating means and means for driving the same, a table for the blank, oppositely disposed cutting and forming members carried by the reciprocating means, a stationary cutting member co-operating with the moving cutting member on one stroke of the reciprocating means, and a stationary forming member co-operating with the moving forming member on the opposite stroke of the reciprocating means.

9. In a machine for cutting and forming box blanks, reciprocating means and means for driving the same, a table for the blank, oppositely disposed cutting and forming members carried by the reciprocating means, a stationary cutting member co-operating with the moving cutting member on one stroke of the reciprocating means, a stationary forming member co-operating with the moving forming member on the opposite stroke of the reciprocating means, means for discontinuing the drive of the reciprocating means just prior to the cutting operation, and means tending to arrest the motion of the parts when the drive is discontinued.

10. In a machine for cutting and forming box blanks, reciprocating means and means for driving the same, a table for the blank, oppositely disposed cutting and forming members carried by the reciprocating means, a stationary cutting member co-operating with the moving cutting member on one stroke of the reciprocating means, a stationary forming member co-operating with the moving forming member on the opposite stroke of the reciprocating means, means for discontinuing the drive of the reciprocating means at a predetermined point in the operation, and means tending to arrest the motion of the parts when the drive is discontinued.

11. In a machine for cutting and forming box blanks, reciprocating means and means for driving the same, a table for the blank, oppositely disposed cutting and forming members carried by the reciprocating means, a stationary cutting member co-operating with the moving cutting member on one stroke of the reciprocating means, a station-

ary forming member coöperating with the moving forming member on the opposite stroke of the reciprocating means, and driving means for the reciprocating means, including a clutch and means normally tending to disconnect the clutch, said means operating just prior to the coöperation of the cutting members.

12. In a machine for cutting and forming box blanks, reciprocating means and means for driving the same, a table for the blank, oppositely disposed cutting and forming members carried by the reciprocating means, a stationary cutting member coöperating with the moving cutting member on one stroke of the reciprocating means, a stationary forming member coöperating with the moving forming member on the opposite stroke of the reciprocating means, and driving means for the reciprocating means, including a clutch, means normally tending to disconnect the clutch, said means operating just prior to the coöperation of the cutting members, and a brake for arresting the motion of the parts when the clutch is disconnected.

13. In a machine for cutting and forming box blanks, coöperating moving and station-

ary cutting members, coöperating moving and stationary corner-forming dies, the moving cutting member and corner-forming die being oppositely disposed, and driving means, including a clutch, means normally tending to disconnect the clutch, said means operating just prior to the action of the cutting members.

14. In a machine for cutting and forming box blanks, coöperating moving and stationary cutting members, coöperating moving and stationary corner-forming dies, the moving cutting member and corner-forming die being oppositely disposed, and driving means including a clutch with a sliding bolt engaging a coöperating abutment, a dog normally tending to enter the path of the bolt and withdraw it, disconnecting the clutch, said dog being timed and placed to accomplish the release of the clutch just prior to the operation of the cutting member.

Signed by me at Baltimore, Maryland,
this 24th day of July, 1919.
